UNITED STATES PATENT OFFICE

FRANCIS NORWOOD BARD, OF HIGHLAND PARK, ILLINOIS

CROSSHEAD

Application filed December 21, 1922. Serial No. 608,367.

My present invention relates in general to cross-heads, and more particularly to a type of cross-head in which provision is made for wear and replacement.

5 In a locomotive, the cross-head reciprocates between guides located immediately to the rear of the cylinders, and forms the pivotal connection between the piston rod and the adjacent end of the pitman or crank. The 10 chief function of the cross-head is to relieve the piston of angular stress from the pitman.

Some parts such as the slippers or shoes, being subject to a greater amount of wear, tear and strain than the cross-head proper, it is 15 desirable to make them readily adjustable to take up the wear or looseness and also readily detachable to permit of replacement. Where such adjustment is provided directly between the cross-head body, and the slippers,

20 I have found in actual operation, that a wearing action is also produced on the cross-head body proper, which requires repair and replacement of that part also. I have therefore found it advisable to so arrange for the 25 desired detachability and replacement of the slippers as to reduce this wear on the cross-head body to a minimum.

Among the more important objects of this invention therefore are: the provision of an 30 arrangement whereby the slippers are mounted for adjustment independently of the cross-head body; the provision in at least one embodiment hereinafter described, of an intermediate member which is detachably but non-adjustably carried from the cross-head body, and upon which in turn the slipper is mounted for relative adjustment; the provision of a slipper so associated as to be at all times 35 freely removable from the cross-head, and more particularly with such association, of an arrangement whereby the movement of the 40 slipper in one direction relatively to the cross-head produces an adjustment thereof in another direction; the provision with a slipper and cross-head of means for giving the slipper a relative movement, which means are at 45 all times freely removable with said slipper; the provision of a plurality of independent means for moving the slipper; the provision 50 of means at each end of the cross-head for

giving the slipper a movement relatively to the cross-head body; the provision of an efficient arrangement for causing a movement of the slipper in one direction to produce a movement thereof in another; and the provision 55 generally of a simplified, new, improved and more efficient cross-head construction of the character described.

Among the additional objects of this invention are the provision of an improved readily 60 detachable and adjustable wearing member or shoe on the cross-head, and the provision in combination therewith, of means movable relative the cross-head and shoe for taking up wear, such means being characterized by 65 the feature of displacing the shoe always parallel to the longitudinal axis of the cross-head, so as to prevent greater wear on one part than on another part.

In the attainment of the objects referred 70 to, together with such additional benefits and advantages as may hereinafter appear or be pointed out, I have provided a construction, which takes form in the several embodiments 75 illustrated in the accompanying drawings in which—

Figure 1 is a side elevational view of the cross-head partly broken away;

Figure 2 is an end elevational view thereof, 80 also partly broken away;

Figure 3 is a side elevational view, partly in section of an alternative form of this invention;

Figure 4 is a plan view of the shoe removed 85 from the cross-head;

Figure 5 is an end elevational view of the device of Figures 3 and 4, parts being in section.

Figure 6 is a side elevational view, partly in section, illustrates a further modified form 90 of this invention.

Figures 7 and 8 are sectional views taken on lines 7—7 and 8—8 respectively, of Figure 6, looking in the direction indicated by the arrows; and 95

Figure 9 is a perspective view of one of the parts of the form shown in Figures 6, 7, and 8.

As the upper and lower halves of the cross-head are in all respects substantial duplicates, I will confine this description to one of 100

the halves for purposes of convenience, which comprises generally three parts, reference here to Figures 1 and 2, namely: the cross-head body 10, the shoe 11, and the slipper or wearing piece 12.

5 The shoe 11 is provided with the inwardly extending walls 13 and 14 having their outer surfaces oppositely inclined as shown at 15 and 15', and arranged to be received in the slot 10 17 in the cross-head body 10, said slot having its opposite walls inclined as shown at 16, 16'. A dove-tail connection is thus afforded between the shoe 11 and the cross-head body 10, by means of which any relative transverse movement of the two is prevented.

15 The shoe 11 is detachably supported upon the cross-head body 10, and retained against longitudinal displacement thereon by the provision of two or more transverse bolts 18—18, 20 the walls 13 and 14, and the walls 19—19 of the cross-head, having complementally arranged transverse apertures 20—21, adapted to be aligned for reception of said bolts

25 The shoe 11 is provided on its outer face with the slot 25 of substantial length and width, in which slot is received the ears 26 and 26' depending from the shoe 11, the ears 26 and 26' being spaced apart preferably a substantial distance and illustrated as positioned adjacent the end walls 27 and 28 of the slot 25, the distance between the outer walls 29 and 30 of the ears 26 and 26' being however shorter than that between the end walls 27 and 28 of the slot 25, to permit of

35 the movement of the ears 26 and 26' in the slot 25 longitudinally of the cross-head. The slot 25 terminates short of either end of the shoe 11, leaving the upstanding end wall portions 31 and 32, which have their top or outer 40 faces 33 and 34 inclined in parallel planes as clearly shown on the left of Figure 1. These walls 31 and 32 are further provided with the slots 35, 36 each open toward and in the direction of the slipper 12, the bottom 37 of each 45 slot being curved as clearly shown in Figure 2, the purpose of which will appear shortly.

50 In viewing Figure 1, it will be seen that the inner or lower surface or wall of the shoe 11 has its end portions 39 and 40 inclined at 41 and 42 oppositely to and in parallelism with the inclined upper portions 33 and 34 of the walls 31 and 32 and it will be further seen that the inclined surfaces 33 and 41, 34 and 42 are preferably of the same length, and that 55 the inclined surfaces of 33 and 34 of the shoe, are spaced apart substantially the same distance as are the inclined surfaces 41 and 42 of the slipper. The ear 26 is spaced at a distance from the inclined portion 41 of the shoe 60 whereas the ear 26' is positioned immediately adjacent the other inclined portion 42 of the slipper.

65 From the structure thus far described, it will be seen that to assemble the slipper 12 on the shoe 11 all that is necessary is to bring

the ears 26, 26' into position into the slot 25 by a movement of the slipper transversely of the cross-head, and that a similar relative movement of the two in the opposite direction will result in a disassembling of the two. It will be further obvious that any relative longitudinal movement between the shoe 12 and the slipper 11 will result in a transverse movement of the two due to the coaction of the two sets of inclined surfaces 33, 41 and 34, 42.

70 The slipper and shoe are shown in Figure 1 at their extreme inner longitudinal position with the ear 26' in contact with the end wall 28 and with the ear 26 at a distance 80 from the other end wall 27 of the slot 25. The ears 26, 26' in this position of adjustment of the slipper are in their position nearest to the longitudinal axis of the cross-head, and are preferably of a length that in this 85 position, their bottom surfaces 43 contact with the adjacent bottom of the slot 25. The ears 26, 26' thus coact with the end walls 27 and 28 and with the bottom of the slot 25 to form stops to limit the relative longitudinal movement of the slipper and shoe.

90 It will be noticed that I have provided two sets of coacting inclined surfaces 33, 41 and 34, 42 to cause the longitudinal movement of the slipper to produce a lateral adjustment 95 thereof, and that these sets of inclined surfaces are positioned at a substantial distance apart and adjacent each end of the cross-head.

99 The slipper 12 is provided on its outer surface 45 with brasses to engage with and slide upon the end or inner face of the guide upon which the cross-head reciprocates. The shoe 11 is provided with the flanges 46 and 47, the inner walls of which are provided with 100 brasses which engage with and slide upon the side or lateral faces of the guide.

105 For producing a relative longitudinal movement between the slipper and shoe, I have provided the ears 26 and 26' each with threaded openings arranged to receive therein the threaded bolt 48 or 49 received loosely in the slots 35, 36 with the bolt heads 50 and 51 in engagement with the opposite ends of the shoe as shown. Each ear receives two 110 bolts as will be clear upon viewing Fig. 2.

When it is desired to produce a lateral adjustment of the slipper 11, the bolts at one end or the other depending upon the direction of adjustment desired are turned to move 115 the slipper longitudinally which will cause a lateral movement of the slipper, the slots 35 and 36 permitting the bolts 50 and 51 to move laterally with the slipper.

120 As will be obvious, the slipper is free at all times for removal from the cross-head merely upon a lateral movement thereof, neither the bolts 50, 51 nor the ears 26, 26', interfering in any way with such movement.

125 As the part of the cross-head engaged by

the slipper is necessarily also subject to considerable wear due to its association with the slipper, I have made provision for this by having the shoe 11, detachably but non-adjustably connected to the cross-head body so as to permit of its removal and replacement having the slipper 12 detachably carried therefrom.

Referring now to the alternative form of the invention illustrated in Figures 3, 4, and 5, and confining the description to one of the halves of the device for purpose of convenience, there is provided the cross-head body 10^a, shoe 11^a, and the slipper or wearing plate 12^a. Thus, essentially the device of Figures, 3, 4, and 5 embody similar elements to those of the device illustrated in Figures 1 and 2.

However, in the device of Figures 1 and 2, the slipper, while in course of adjustment, carries the bolts 50 and 51 with it, and the structure now to be described eliminates the necessity of laterally slidably mounting the retaining and adjusting bolts, and accomplishes this by mounting such bolts for lateral angular displacement.

In carrying out the feature mentioned above, the cross-head is provided with longitudinal spaced parallel side walls 54 and 55, which are provided with the inclined internal surfaces 56 and 57, said walls being joined at one end of the cross-head, preferably the front end, or the part nearer the piston rod by an abutment 58 and affording at the other end an entrance 59 through which the depending walls 60 and 61 of the shoe may be introduced. These walls afford a space 62 for giving the shoe a certain amount of inherent resiliency and also affording a chamber in which certain parts to be presently described are contained. The walls 60 and 61 are provided with inclined outer surfaces 63 and 64, respectively, and said surfaces are adapted to fairly snugly contact with the surfaces 56 and 57 of the walls 54 and 55 when the shoe is inserted.

The abutment 58 is provided with an inclined inner surface 65 which is adapted to engage a complementary inclined surface 66, formed on a transverse abutment 67, which latter is formed integrally with the inner surface of the shoe. The abutment is provided with inclined surfaces 67^a, which engage the surfaces 56 and 57. The abutment 67 is provided with a forwardly extending portion 68 which is adapted to overlie the abutment 58, as best seen in Figure 3. The walls 60 and 61 terminate short of the abutment 67, for a purpose which will presently appear.

The shoe, after having been inserted, is non-adjustably retained on the cross-head by the provision of a transverse bolt 69, which passes through complementary openings in the walls 54 and 55 of the cross-head, and between two transverse webs 70 and 71, integrally

or otherwise formed with the shoe 11^a, and disposed toward the rear end of the chamber 62. It will be obvious that when the bolt is placed in the position shown in Figure 3, the shoe is effectively retained against longitudinal displacement relative to cross-head, the webs 70 and 71 and the inclined surface 66 cooperating to this end. Furthermore the dove-tail connection afforded by the inclined surfaces 56, 57, 63, 64, 65 and 66, effectively prevents outward displacement of the shoe. As a further means for preventing dislodgment of the shoe or undue vibration thereof, there is provided a short bolt 72 having its head 73 seated in the abutment 67, which bolt projects through an opening 74 in the abutment 58 and receives a retaining nut 75 on its projecting end, which nut 75 engages the outer surface of abutment 58, as best seen in Figure 3.

From an inspection of Figures 3 and 5 it will be observed that the upper part of the shoe is provided with a channel 76, bordered by parallel flanges 77-77, and in said channel there is placed the slipper or wearing plate 12^a, which slipper is intended to be constructed of a proper wearing material and forms the principal surface of contact between the device and the cross-head guide, not shown.

The slipper is longitudinally and laterally adjustable on the shoe for the purpose of taking up wear, and to the end that this function may be accomplished, while the cross-head is in its guides, without subjecting the parts to the necessity of complete disassembly, and in order to eliminate chattering or other vibration of the slipper, there are provided the sets of adjusting and retaining rods or bolts 79 and 80, said bolts being arranged to move the slipper longitudinally, and also adapted for angular displacement.

The inner surface of the slipper is, for the greater part of its length, parallel to the outer surface, but at the proper points the slipper is internally provided with inclined surfaces 81, 82, and 83, said surfaces being complementary to and in engagement with inclined surfaces 84, 85 and 86, said latter mentioned surfaces being formed on the extension 68, transverse web 87, and end abutment member 88, respectively, the web 87 and abutment 88 being integrally formed with the shoe 11^a.

As best seen in Figure 4, the sets of rods 79 are arranged in a multiple of two, one rod being placed on each side of the longitudinal axis of the cross-head, in spaced relationship, and both rods having threaded portions 89 which pass through threaded openings in a transverse rocker bar 90, the latter lying in a recess 91 in the under-surface of the wearing plate 12^a, and furthermore being retained against displacement from said recess by the

provision of a curved flange 92, formed integrally with said wearing plate. The wearing plate is furthermore recessed at 94 to accommodate the projecting parts of the rods 79.

5 The rods 79 pass through suitable enlarged openings 95 provided in the abutment 67, as best seen in Figure 3, and on said rods are provided sleeves 96, the inner ends 97 of which are hemispherically formed to seat in similarly formed recesses 98 in the abutment 67. Heads 99 are provided on the rod 79, and said heads abut the outer ends of the sleeve 96. The sleeves and the head of the adjusting rods in this instance lie within openings 101—101 provided in the abutment 98. The heads 99 of the rods lie beyond the abutment so as to be readily accessible for turning. It will be observed that the opening 95 and the openings 100 are of sufficient area 26 to permit of angular displacement of the rods in their sockets. The walls 60 and 61 terminate at the points seen in Figure 4 in order to afford space for the rocker bar 90.

At the other end of the cross-head, and operating oppositely to the rods 79 there are provided the rods 80, referred to hereinbefore, and these rods are similarly arranged in a multiple of two and pass through a suitable transverse rocker bar 90^a which seats in 30 a recess 91^a, provided in the under surface of the slipper 12^a, and said bar is retained in said recess by the provision of a curved flange 92^a.

The rods or adjusting bolts 80 pass through 35 spaced tapered openings 101 in the abutment 88, and similarly to the rods 79, said rods 80 are provided with hemispherical portions 102 which seat in similarly formed sockets 103 in said abutment 88. The outer ends of the 40 rods 80 are provided with heads 104, which are readily accessible for adjusting the slipper.

It will be seen from inspection of Figures 3 and 4 that the structure of the shoe is substantially skeleton, and is filled by the insertion and securing of the wearing plate 12^a. This arrangement makes for light construction, and at the same time does not weaken the device.

50 When it is desired to adjust the slipper on the shoe, one or the other of the sets of adjusting rods is manipulated to longitudinally displace said slipper. Of course, when the slipper is originally placed on the crosshead, it is in the position shown in Figure 1, but as the outer surface thereof gradually wears, the bolts 80 are turned to move the slipper toward the rear end of the cross-head, the bolts 79 being first released to permit of such 55 displacement. When the slipper is in the proper position, both of the sets of bolts are tightened and the slipper is again ready for use.

65 It will be observed that it is possible to replace the slipper or shoe, if necessary, while a

locomotive is in service without removing the cross-head from its guides, as a new shoe and slipper may be inserted between the cross-head and the guide by first removing bolts 69 and 72 and then removing the damaged 70 worn-out shoe or slipper, and then placing the new shoe with its slipper in position. The openings 100 are of sufficient size to permit the heads 99 of the rods 79 to be drawn to the rear through said openings. After the new 75 slipper and shoe have been placed in position on the cross-head the slipper may be adjusted into proper wearing position in the manner previously explained.

Referring now to the form of the invention 80 shown in Figures 6, 7, 8, and 9, there is provided a cross-head 10^b having an integral axial collar 105 at the forward end for receiving a piston rod 106. The cross-head is preferably hollow to afford a chamber 10^c, 85 and the walls 107 of said chamber are provided with aligned openings 108—108 for receiving a transverse pin (not shown) affording a connection between the cross-head and the driving rod (not shown), which is usually 90 provided.

The upper and lower portions of the cross-head, assuming that the cross-head is employed on a steam locomotive, are provided with tapered dove-tail connections for receiving and supporting the shoes 11^b—11^b, which shoes engage opposed guides, not shown. As both of the shoes and the parts of the cross-head adjacent thereto are identical in 95 construction I will describe but one of the 100 same.

As best seen in Figures 7 and 8 the cross-head is provided with a tapered dove-tail slot 109 which extends from a terminal pocket 110 at the forward end of the cross-head 105 and opens at the rear end of the cross-head. The base of the groove 109 has a plain surface 111, and the shoe 11^b is provided with a longitudinal abutment 112 which is tapered longitudinally to fit snugly in the slot 109 when 110 the cross-head and shoe are first assembled. The relationship of the abutment and the slot are such that when the parts are first assembled the forward edges 113 and 114 of the shoe and cross-head respectively are in 115 vertical alignment.

The abutment 112 carries a plurality of transversely arranged bolts 115 which project through the walls 116 of the cross-head bordering the groove and engage each in 120 one of the complementary slots 117—117 in said walls.

The shoe is adapted to be longitudinally adjusted upon the cross-head for the purpose of taking up such wear as may occur on the 125 outer surface 118 of the shoe, and to this end the abutment 112 is provided, as best seen in Figure 9, with a longitudinal groove 119 for receiving the shank 120 of a wedge device adjustable on said shoe. The two por- 130

tions of the abutment spaced apart by the formation of said groove are provided with forwardly inclined surfaces 121—121, 122—122, and the shank 120 is provided with complementary laterally extending tapered tongues 123 and 124, which are adapted to engage the surfaces 121 and 122, respectively, as best seen in Figure 1.

When the parts are assembled the under surface 125 of the abutment 112 and the under surface 126 of the shank 120 are flush and engage evenly the surface 111. A threaded rod 127 is provided on the shank 120 and projects through a vertical slot 128 provided 15 in a lug 129 formed integrally on the bottom rear portion of the shoe. Lock nuts 130—130 serve to retain the rod and the shank in adjusted position on the shoe.

When the outer surface 118 of the shoe becomes worn it is necessary that said shoe be moved outwardly from the cross-head in order that the latter will move snugly between its guides (not shown) and this is accomplished by moving the shank 120 by 20 means of the rod 127 toward the forward end of the cross-head. This movement causes the wedge elements 123 and 124 to force the surfaces 111 and 125 apart and thus adjust the shoe to the proper position. Previous 25 to such adjustment the bolts 115 must be loosened to permit a rearward displacement of the shoe on the cross-head. When the shoe has thus been laterally and longitudinally displaced by relative movement 30 thereon of the wedge members, the nuts on the rod 127 are again tightened, and the adjustment is thus maintained.

It is to be observed that the provision of the shank 120, as shown, and the two sets of 35 inclined elements thereon, insures that the outer wearing surface of the shoe will always be parallel to the longitudinal axis of the cross-head. Furthermore, the under surfaces of the shank and inclined elements afford a substantial area of contact with the base of the cross-head groove and will prevent rocking or chattering of the shoe on the cross-head.

Having thus described my invention and illustrated its use, what I claim as new and desire to secure by Letters Patent is:

1. In a device of the character described, in combination, a cross-head and a slipper movable longitudinally of the cross-head and freely removable therefrom at all times, means for causing said slipper to move laterally of the crosshead upon a relative longitudinal movement between the two, and an angularly displaceable pivoted member for setting up such relative movement.

2. In a device of the character described, in combination, a cross head, and a slipper freely removable therefrom at all times, and means for giving said slipper a movement laterally of the cross head including surfaces

on the slipper and cross head in direct engagement with each other and an angularly displaceable pivoted member connecting said crosshead and slipper.

3. In a device of the character described, in combination, a cross head, and a slipper, and means for giving the slipper a movement longitudinally of the cross head comprising a pivoted member which during such movement has a threaded engagement with the slipper and a sliding engagement with the cross head.

4. In a device of the character described, in combination, a cross head and a slipper movable relatively thereto, and separate relatively angularly displaceable pivoted means displaceable relatively to said cross-head for moving said slipper in opposite directions.

5. In a device of the character described, in combination, a cross head and a slipper, and means for varying the position of the two including coacting surfaces at each end of the cross head and angularly displaceable pivoted members for setting up relative movement between said crosshead and slipper.

6. In a device of the character described, in combination, a cross-head having a shoe whose surfaces are adapted to engage the lateral faces of the guide, said shoe being fixed to the cross-head against adjustment, a slipper separate from said shoe adapted to engage another face of the guide, said slipper being freely removable at all times from the cross-head, means for pulling the slipper along the cross-head, the cross-head and slipper being arranged and constructed to cause a lateral adjustment of the slipper upon a relative longitudinal movement of said cross-head and slipper.

7. In a device of the character described, in combination, a cross-head, a readily detachable shoe on said cross-head, an adjustable plate on said shoe, and an angularly displaceable pivoted means for retaining said plate in position on said shoe.

8. In a device of the character described, in combination, a cross-head, a readily detachable shoe on said cross-head, a wearing plate on said shoe, and pivoted means angularly displaceable relative to the longitudinal axis of said cross-head for adjustably retaining said plate.

9. In a device of the character described, in combination, a cross-head, a readily detachable shoe on said cross-head, a wearing plate supported by said shoe, and angularly displaceable pivoted elements for adjusting said wearing plate.

10. In a device of the character described, in combination, a cross-head, a shoe for said cross-head, a slipper carried by said shoe, and provided with inclined surfaces engaging the shoe, and angularly displaceable pivoted means for moving the slipper on said shoe.

11. In combination, a crosshead and a slip-

- per, and means for giving the slipper movement relatively to the crosshead including angularly displaceable threaded members at opposite ends of the crosshead.
5. 12. In a device of the character described, in combination, a cross-head, a shoe detachably secured to said cross-head and provided with abutment surfaces angularly disposed with respect to the longitudinal axis thereof, 10 a slipper supported by said shoe and provided with abutment surfaces complementally arranged with respect to the first mentioned surfaces, and angularly displaceable pivoted elements engaging said shoe and slipper for 15 retaining the latter in position on the shoe.
13. In a device of the character described, in combination, a cross-head, a shoe detachably secured to said cross-head and provided with abutment surfaces angularly disposed 20 with respect to the longitudinal axis thereof, a slipper supported by said shoe and provided with abutment surfaces complementally arranged with respect to the first mentioned surfaces, and adjustable means having 25 pivotal engagement with said shoe and slipper for adjusting the latter on said shoe. 90
14. In a device of the character described, in combination, a cross-head, a shoe detachably secured to said cross-head and provided 30 with abutment surfaces angularly disposed with respect to the longitudinal axis thereof, a slipper supported by said shoe and provided with abutment surfaces complementally arranged with respect to the first mentioned 35 surfaces, said shoe and slipper being provided with recesses, and an angularly displaceable threaded element engaging said recesses for retaining the slipper on said shoe. 95
15. In a device of the character described, 40 in combination, a cross-head, a shoe detachably secured to said cross-head and provided with abutment surfaces angularly disposed with respect to the longitudinal axis thereof, a slipper supported by said shoe and provided 45 with abutment surfaces complementally arranged with respect to the first mentioned surfaces, said shoe and slipper being provided with recesses, and an adjustable element pivotally engaging said recesses for 50 adjustably retaining the slipper on said shoe. 100
16. In a device of the character described, in combination, a cross-head, a readily detachable shoe on said cross-head, a wearing plate on said shoe, and a plurality of bolts longitudinally disposed in the shoe and angularly displaceable relative to the longitudinal axis of said cross-head for retaining said plate. 105
17. In a device of the character described, in combination, a cross-head, a readily detachable shoe on said cross-head, a wearing plate on said shoe, and pivoted means angularly displaceable relative to the longitudinal axis of said cross-head for retaining said plate, said shoe, slipper and angularly displaceable means forming a complete unit. 115
18. In a device of the character described, in combination, a cross-head, and a slipper movable longitudinally of the cross head and freely removable therefrom at all times, means integral with the cross head and the slipper for causing said slipper to move laterally of the cross head upon a relative longitudinal movement between the two, and a plurality of pivoted oppositely disposed angularly displaceable members for setting up such movement. 120
